UNITED STATES PATENT OFFICE.

ALVA M. COLT, OF BATAVIA, NEW YORK, ASSIGNOR OF ONE-THIRD TO JAMES R. COLT, OF BATAVIA, NEW YORK.

LIFTING-JACK.

No. 922,856.

Specification of Letters Patent.

Patented May 25, 1909.

Application filed May 6, 1908. Serial No. 431,231.

To all whom it may concern:

Be it known that I, ALVA M. COLT, a citizen of the United States, residing at Batavia, in the county of Genesee and State of New York, have invented a new and useful Improvement in Lifting-Jacks, of which the following is a specification.

This invention relates to lifting jacks and more particularly to lever-operated jacks 10 suitable for lifting automobiles or wagons.

The objects of the invention are to produce a powerful lifting jack of compact, simple and inexpensive construction in which the weight can be either raised or lowered step 15 by step by like motions of the hand lever; also to produce a jack composed of few parts of simple and strong construction which are separable and can be readily assembled for use and taken apart to enable them to be 20 more readily stored away or transported; also to construct the jack so that the lifting dogs can be arranged very close to the lifting bar to give a powerful leverage with a short hand lever; and also to provide a novel spring 25 device for controlling the action of the lifting dogs to enable the lifting bar to be moved at will in either direction by the same motion of the lever.

In the accompanying drawings, consisting 30 of two sheets; Figure 1 is an elevation, partly in section, of a lifting jack embodying the invention. Fig. 2 is a detached perspective view of one of the lifting dogs. Fig. 3 is a fragmentary transverse sectional elevation of 35 the jack. Fig. 4 is a detail sectional elevation of the turn button for controlling the direction of movement of the lifting bar. Fig. 5 is a fragmentary sectional elevation of the parts of the jack separated. Fig. 6 is a fragmentary sectional elevation of the jack, in 40 line 6—6, Fig. 3, showing the same adjusted for raising the lifting bar. Fig. 7 is a similar view thereof, showing the jack adjusted for lowering the lifting bar. Fig. 8 is a horizontal section in line 8—8, Fig. 6.

Like letters of reference refer to like parts in the several figures.

A represents the standard or frame of the jack, B the toothed lifting bar, C the hand lever, and D D' the dogs for operating the 50 lifting bar.

The standard may be of any suitable construction, but preferably consists, as shown, of a hollow column or pipe a screwed at 55 opposite ends into a base a', and a frame or

casting a² having lever openings a³ at opposite sides thereof.

The lifting bar B is movable vertically in and is guided by the standard, and is provided at its upper end with a suitable lifting 60 head b and at opposite sides with ribs formed with ratchet teeth b'.

The lever C extends into the standard frame a² through one of the side openings thereof and is provided at opposite sides with 65 projecting trunnions c which rest in open seats c', Figs. 3 and 5, provided therefor in the inner sides of the opposite portions of the frame a². Open-ended horizontal grooves c² in the opposite sides of the frame lead from 70 the openings a³ of the frame to said trunnion seats to guide the trunnions into the seats when placing the lever in the standard. A hole c³, Fig. 3, extends vertically through the 75 inner end of the lever through which the lifting bar passes.

The lifting dogs D D' are pivoted in the hole c³ of the lever at opposite sides of the lifting bar so that their upper ends or noses can swing into and out of engagement with 80 the teeth of the lifting bar. The dogs preferably have integral pivot trunnions or studs d at opposite sides which rest in open seats d' in the lever at opposite sides of the hole c³ thereof, and the dogs are preferably hollow 85 or of U-shape in cross section, as shown in Fig. 2, so that the sides of the dogs can straddle the toothed ribs of the lifting bar. This construction of the dogs enables them to be located closer to the lifting bar than solid 90 dogs of the same size and strength could be, and this close arrangement of the dogs gives an increased leverage. The distribution of 95 the weight of the metal in the dogs is such that their upper ends tend to swing away from the lifting bar and rest against the upper edges of the end walls of the hole c³ in the lever, see the dog D' in Fig. 7.

E, Figs. 3, 6 and 7, represents a spring for causing the noses of the dogs to engage the 100 ratchet teeth of the lifting bar for raising the same. This spring preferably consists of a resilient wire bent to the shape shown in Figs. 6 and 7. It is secured centrally by a screw e, or other means, to one side of the 105 standard frame a² above the dogs and has two legs or side portions which have spring coils and extend downwardly from the securing screw and have outwardly bent lower portions with inbent ends e'. The legs of the 110

spring normally tend to close toward each other, as shown in Fig. 6, and when in this position their inbent ends bear on lugs e^2 on the dogs and press the noses of the dogs into engagement with the teeth of the lifting bar.

F represents a turn button or device for spreading the legs of the spring to lift their ends off of the lugs on the dogs so that the dogs will be free to swing by gravity away from the teeth of the lifting bar, as before stated. The turn button consists of a short shaft passing through a hole in the side of the standard frame and having a thumb piece or handle at its outer end for turning it and an elongated head f at its inner end located between the legs of the spring and having notched ends adapted to engage the legs of the spring and spread the same when turned from the vertical position shown in Fig. 6 to the horizontal position shown in Fig. 7. The turn button preferably has a lug f' , Fig. 4, entering a segmental recess f^2 in the standard frame and adapted to strike the ends of said recess to limit the rotary movement of the turn button. The legs of the spring E bearing against the head f hold the turn button in either position to which it is turned.

The spring E could be of somewhat different shape than shown in the drawings and still operate in the same manner, and instead of the two legs or portions of spring being made in one integral piece, it will be manifest that the two portions could be separate pieces suitably secured in place, and the term "spring" is employed in this specification with this broader meaning. Any other suitable device could be used in place of the turn button for spreading the legs of the spring.

The operation of the jack is as follows: If it is desired to raise the lifting bar the turn button F is turned to the vertical position shown in Fig. 6, which allows the legs of the spring to close toward each other and press the noses of the dogs into operative engagement with the teeth of the lifting bar. Then by oscillating the hand lever the dogs are alternately raised and lowered. When the lever is forced downwardly the dog D ascends and engaging under one of the ratchet teeth raises the lifting bar while the other dog D' slides downwardly over the inclined face of one of the teeth and is caused to snap under the tooth by the spring. When the lever is raised the dog D' ascends and lifts the bar while the dog D descends and takes a new hold, so that the lifting bar and the weight thereon are raised the length of one tooth with each movement of the lever. To lower the weight the turn button is turned to the horizontal position shown in Fig. 7, which spreads the legs of the spring E, lifting its ends off of the lugs on the dogs. Then when

under one of the teeth descends and lowers the lifting bar and the other dog D ascends, being held by its weight out of engagement with the teeth of the bar until the upper edge of the end wall of the hole c^3 in the lever strikes the dog and presses it inwardly beneath one of the teeth, when, by the continued downward movement of the lever, the ascending dog takes the load off of the descending dog, which then swings by gravity clear of the teeth. Upon raising the lever the dog D descends and lowers the lifting bar and the other dog D' rises to take a new hold on another tooth in the same manner as the other dog D when the lever was lowered, the dogs thus acting alternately to lower the lifting rod and its weight the length of one tooth with alternate up and down movements of the lever. When the spring E is spread, as explained, to cause the lowering of the lifting bar, its ends are held in a position to strike the lugs on the dogs as the dogs approach the upper limit of their movement, and throw the dogs into engagement with the ratchet teeth. Thus the spring alone would serve to actuate the dogs to either raise or lower the lifting bar, but the end walls of the hole c^3 of the lever arranged as described for positively actuating the dogs for lowering the lifting bar are desirable and are preferably employed.

The spring E is secured in the standard and is not connected with the pawls but is simply adapted to bear against them, and when the legs of the spring are spread apart by turning the turn button F to the horizontal position, the lever with the dogs in place thereon can be readily placed in position in and removed from the standard, the lifting bar B of course being first taken out of the standard. The dogs are removably seated in the lever and can be removed from the same when the lever is taken out of the standard.

I claim as my invention:

1. In a lifting jack or the like, the combination of a standard, a lifting bar movable therein provided with oppositely disposed ratchet teeth, a lever fulcrumed on said standard, dogs carried by said lever at opposite sides of its fulcrum for engaging said ratchet teeth, a spring secured to said standard, means for adjusting said spring to cause it to engage and press said dogs into engagement with said ratchet teeth at the end of the down strokes of said dogs for raising said lifting bar or to leave the dogs free to swing out of engagement with said teeth at the end of the down strokes of the dogs for lowering said lifting bar, and parts which engage said dogs and move them into engagement with said ratchet teeth at the end of their up strokes when they are left free by said spring, substantially as set forth.

2. In a lifting jack or the like, the combination of a standard, a lifting bar movable

therein provided with oppositely disposed ratchet teeth, a lever fulcrumed on said standard, dogs carried by said lever at opposite sides of its fulcrum for engaging said 5 ratchet teeth, a spring secured to said standard, and means for adjusting said spring to one position in which it presses said dogs against said ratchet teeth for raising said lifting bar or to another position in which it 10 leaves said dogs free to swing away from said ratchet teeth at the end of the down strokes of the dogs and remain out of engagement with said teeth during a part of the up strokes of said dogs and then moves said dogs 15 into engagement with said ratchet teeth at the end of their up strokes for lowering said lifting bar, substantially as set forth.

3. In a lifting jack or the like, the combination of a standard, a lifting bar movable in 20 therein and provided with oppositely disposed ratchet teeth, a lever fulcrumed on said standard, oppositely arranged dogs pivoted on said lever at opposite sides of its fulcrum for engaging said ratchet teeth, a 25 spring secured to said standard and having opposite legs for pressing said dogs into engagement with said ratchet teeth for raising said lifting bar, means for spreading said legs of the spring to leave said dogs free to swing 30 by gravity away from said ratchet teeth at the end of the down strokes of the dogs for

lowering said lifting bar, and parts on said lever for moving said dogs into engagement with said ratchet teeth at the end of their up strokes when they are thus freed from said 35 spring, substantially as set forth.

4. In a lifting jack or the like, the combination of a standard, a lifting bar movable in said standard and having oppositely arranged ratchet teeth, a lever fulcrumed on said 40 standard, dogs pivoted on said lever at opposite sides of its fulcrum to coöperate with said ratchet teeth, a spring secured on said standard above the fulcrum end of said lever and having opposite legs which, when left 45 free to spring toward each other, press said dogs into engagement with said ratchet teeth for raising said lifting bar, a turn button on said standard between said spring legs and adapted to be turned to spread said spring 50 legs apart to leave said dogs free to swing away from said ratchet teeth for lowering said lifting bar, and means for moving said dogs to engage said teeth at the end of their up strokes when said dogs are free from said 55 spring, substantially as set forth.

Witness my hand, this 24th day of April,
1908.
